Inventor,

John Merry
by his Atty
J. S. Darrow

United States Patent Office.

JOHN MERRY, OF NEW YORK, N. Y.

Design No. 4,304, dated August 23, 1870.

DESIGN FOR ASH-PAILS.

The Schedule referred to in these Letters Patent and making part of the same.

To all whom it may concern:

Be it known that I, JOHN MERRY, of New York city, in the State of New York, have invented and produced a new and original Design for Ash-Pails, which may be used also for other articles of sheet metal of a form approximating the cylindrical.

The following is a specification:

The nature of my design is fully represented in the accompanying drawing, to which reference is made.

Figure 1 is a side elevation, and

Figure 2 is a horizontal section.

The approximately cylindrical surface is ribbed or beaded with ridges, which are distributed with wide and nearly equal spaces between them. The beads extend nearly to the top and bottom, but not quite. They die out near the top and near the bottom.

I claim as my invention—

The cylindrical longitudinally-ribbed design, as represented, for ash-pails and analogous articles.

JOHN MERRY.
